FORCE APPLYING MECHANISM

Gregor L. Lang, Suffield, Conn.

Application November 13, 1950, Serial No. 195,249

7 Claims. (Cl. 200—98)

This invention relates to a new and improved force applying mechanism or actuator.

An object of the invention is to provide a new and improved force applying mechanism which is capable of employment in electrical apparatus or otherwise.

Another object of the invention is to provide such a device which may be termed an overthrow control actuator which is capable of many uses including electrical and mechanical apparatus, hydraulic valves and various other apparatus.

Another object is to provide such an actuator for control mechanisms such as valves, switches or the like, of such character as to remove the ambiguity due to two opposed mechanical forces, functioning only when one force is present.

Another object of the invention is to provide a new and improved electrical apparatus embodying such device.

Another object is to provide a new and improved three position force applying or controlling mechanism.

Another object is to provide an electrical relay having three switching positions which is operable by two coils or control circuits and which has unusual stability against vibration, shock and acceleration.

Another object is to provide a new and improved holding relay.

Another object is to provide an arrangement for applying unidirectional forces to an actuated member in such manner that one force only can move the actuated member at one time and the force first applied disables the mechanism of the opposite side and therefore prevails and if both forces are applied simultaneously, they are mutually disabling and no power, force or response is delivered to the actuated member.

Another object is to provide a two position relay apparatus embodying the invention set forth in the preceding paragraph and wherein the disabling effect is obtained by the combination of a resilient member used in combination with a linkage so connected that each armature can force the actuated member to move only through the medium or linkage provided by the opposing armature or associated therewith and the act of energizing one armature causes it to exert a force upon the actuator member by way of or through the medium of the opposite armature or its linkage, and only so long as said opposite armature and linkage is in a state of freedom. Either armature so energized performs its function through the opposite free armature and should the opposite armature not be free, as in case of being simultaneously energized, it will no longer be free to serve as a link for the first armature, instead, it will move to a new locked-up or unfree position and in so doing compresses the spring, introduces freedom or lost motion into the over all system in such manner as to break the path through which the first armature would otherwise apply its force to the actuated arm.

Another object is to provide a device of the type set

2

forth which is relatively economical in design and manufacture and which has fewer parts than prior relays not possessing the functions of the invention and wherein normal back lash and linkage lost motion are fundamentally zero.

Another object is to provide such a device which is of such positive nature that the indeterminate effects due to simultaneous or overlapping pulsing of both coils or control circuits are completely eliminated, the switching function being rendered inoperative or disabled, that is, remaining in its previous position for the duration of such double pulse and wherein the only control signal capable of causing any change is a single pulse applied to the coil opposite that last previously pulsed.

Another object is to provide such a device having the above described pulse discrimination and anti-confusion characteristics but which is optionally operable in normal "current off" circuits with momentary "on" pulses applied for actuation, or in inverted circuits in which current

is normally on in both coils, and in which actuation is secured by momentary breaks, or "current off" pulses in one coil circuit or the other.

Another object is to provide such a device which is capable of functioning as a pulsed "binary" in computing and counting circuits as an alternate positioning or sequence relay.

Another object is to provide a device which may be held in a central, "central off" or "central on" position by simultaneous current and tumbling either way by interruption of either coil circuit.

Another object is to provide a relay of such character that four control functions may be secured with a two coil relay by proper sequencing of single and simultaneous pulses.

Another object is to provide a sensitive relay or a sensitive holding type relay of such unusual nature that as adjustment is made to increase the sensitivity, contact pressures are made greater which is desirable.

Another object is to provide a sensitive relay of such character that operation may be from a closed air-gap condition where flux and forces are highest and actuation is secured by relatively feeble pulses of current in a direction to decrease the currents by small amounts and thus secure large diminutions of flux and pulling force,

that is, it might be described as a releasing relay rather than a "pulling in" relay which is the usual type and is characterized by the fact that it starts its motion from an open gap position where pull is weakest and finishes its motion with a closed gap where pull is strongest but generally least needed.

Another object is to provide a relay construction wherein conventional expensive hinge members and pins are eliminated and in which moving parts are held in operable and assembled relation by functional parts and tensions.

Another object is to provide a relay in which the number of non-functional parts and fastenings is reduced and in which the assembly in working relationship is accomplished by the functional members themselves.

Another object is to provide a new and improved linkage for relays which allows the obtaining of the above objects and advantages.

Other objects and advantages will be apparent from the following description taken in connection with the accompanying drawings. It will be understood that changes may be made in the details of construction and arrangement of parts shown and described and the invention has been shown applied to a relay for the purpose of illustration only.

Referring to the drawings:

Fig. 1 is a front view of a relay apparatus embodying the invention;

- Fig. 2 is a rear view thereof;
 Fig. 3 is a side view thereof;
 Fig. 4 is a top view thereof;
 Fig. 5 is a bottom view thereof;
 Fig. 6 is a view similar to Fig. 1 but illustrating a step in the operation of the device; and
 Fig. 7 is a view similar to Figs. 1 and 6 but illustrating a further step in its operation.

Referring more particularly to the drawings wherein reference characters designate corresponding parts throughout, the device shown embodying the invention is a two position relay of the two magnet, pulse operated type which might be variously described as a latching relay, mechanical hold relay, tumbler relay or an overthrow relay and could by minor variations be given a third position making it a three position tumbler or holding relay.

In the relay shown embodying the invention, is illustrated one form of the new and novel linkage arrangement which connects the two armatures to each other and each to the actuating arm which presses against the contact stacks and permits the relay to function in new manners and in new circuits, hitherto not possible with latching or pulse operated relays.

In addition to the novel functional features made possible by this linkage, the execution shown contains a number of features of such character as to increase the magnetic pull for a given number of ampere turns while improving manufacturability, decreasing cost, and greatly simplifying assembly and adjustment procedure. While the relay shown performs all of the basic functions of a holding relay, and in addition a number of new and important functions and uses, yet it is of such design as to reduce the bulk, complexity and cost below that of conventional holding relays.

The apparatus shown embodying the invention comprises an iron base 10 on which are secured a pair of spaced parallel electromagnet members consisting of coils 11 and 12 on cores 13 and 14 respectively which are secured in position on base 10 by screws 15, or other suitable means.

Secured to base 10 is also the iron frame 16 which extends from base 10 between coils 11 and 12 and has a portion 17 extending above coils 11 and 12.

On opposite sides of frame 16, and adjacent its upper end are provided the pair of L-shaped armatures 18 and 19 each of which is pivotally mounted on its respective side of frame 16 by means of dome or ball ends 20 on pivots 21 which extend through frame 16 and which extend into openings in the adjacent side of armatures 18 and 19. The projection of the dome-ended pivot pins is such as to provide independent pivotal mounting of the two armatures allowing a slight angular freedom or pivotal motion of said armatures, while maintaining a slight spacing between said armatures and the central vertical iron member, along the plane of the two domed pivots.

The armatures 18 and 19 each have a portion overlying the core of its respective coil and is adapted to be pulled or attracted by said coil core upon energization of the coils and said armatures have their angular offset portions positioned between the coils and the frame 16 and pivotally connected thereto as previously stated. The effect of the downward projecting portions of the armatures, cooperating with the central structural or magnetic member, is to provide a magnetic path therebetween of unusually low leakage or reluctance, while at the same time providing a source of additional tractive effort which operatively adds to the pull or tractive effort due to the more normal magnetic pull exerted in the area of juxtaposition of the horizontal portion of the armature and the coil core face.

Each of the armatures has an upwardly extending arm or lug 20 and 21 in aligned relation with each other and adapted to be connected by machine screw 22 which is

5 tightly or permanently affixed to one of the upraised armature extension arms 20 or 21 and passes freely through the aligned clearance hole or opening in the other of said arms and has the coil spring 23 on its shank and the assembly retained in assembled relation by nut 24 which is threaded on screw 22. The compression spring 23 thus draws extensions 20 and 21 together and retains them in adjacent relation for movement of the armatures as a unit about their pivots until sufficient force is applied to overcome said spring 23. The screw 22 could consist of a stud, welded or riveted or otherwise secured to one of the arms.

10 Each of armatures 18 and 19 also have an integral lug 25 and 26 respectively adjacent their lower ends on the side opposite the upraised arms and adapted to extend through a slot 27 in actuator arm 28 which is pivotally mounted to frame 16 adjacent the upper end 17 of frame 16 by pivot 29 and which has its notched lower end 30 in engagement with tumbler or overthrow detent 31 15 which extends into a depression in the upper surface of spring member 32 which has two hook portions partially encircling frame member 16, to accurately position said spring member in a horizontal plane, while permitting vertical freedom whereby it presses upward against tumbler member 31. Spring member 32 is substantially L shaped, the horizontal portion being downwardly arched in such manner that its lower face bears against the frame base member 10 while the depression in its upper face bears upward against the aforesaid tumbler member 31. The vertical portion of spring member 32 extends well up along frame 16, and has threaded into its upper portion a spring tension adjusting screw 33 which bears against frame member 16, and is secured to spring member 32 by lock-nut 40. The function of 20 tension adjusting screw 33 is to force the vertical portion of spring member 32 outwardly from the frame 16, and thus by a rocking motion cause the depression near the extreme end of its horizontal portion to press upward with increased spring force, against tumbler member 31. The vertical extension of spring member 32 is for improved accessibility of adjusting screw 33 and lock nut 40, when the relays are mounted in groups or in restricted spaces.

25 On frame 16 are carried the contact carrying members 34 and 35 having contacts adapted to be actuated by insulators or insulating buttons 36 and 37 on opposite sides of actuator arm 28.

30 In the example shown, the maintenance of the armatures 18 and 19 in firm and pivotable engagement with the dome ended pivots is secured by the pressure of the lower armature extension lugs 25 and 26, cooperatively engaged in, and pressing outwardly against the margins of the elongated slot 27 in the actuator arm 28, said outward pressure being obtained by the inward pressure of 35 the spring-machine screw assembly affixed to the two upraised extension arms which form a part of each armature, said spring urging the upraised arms 20 and 21 inward or toward each other. The leverage exerted by the spring 23 acts across the fulcrum represented by the dome pivots, to press the lower armature extension lugs 25 and 26 outwardly against the margins of the slot 27 in the actuator arm 28, with a force determined by the position of the spring compression adjusting nut 24. A stable assembly is secured by so positioning the upraised arms 20 and 21 that a line connecting the axis of the spring 23 and the contact point of the lower extension lugs, passes diagonally between the two domed contact pins.

35 The armatures are operatively connected together by the couple represented by the mutual engagement of the lower armature extension lugs 25 and 26 in the ends of slot 27 in actuator arm 28, and the pre-adjusted expansive force of spring 23 acting through machine screw 22 which tends to continuously force upraised arm members 20 and 21 together.

In operation, each of the electromagnets is energized in sequence, thus attracting its respective armature, and as the armatures are operatively interconnected as above described, both armatures will move as a unit, with the attracting of one causing simultaneous movement of both, the opposite or free armature being moved away from its associated electromagnet pole face.

Tracing the path of force application, it will be seen that the attracting of either armature by its associated electromagnet, causes the force to be applied by way of the associated upraised arm, to the pre-loaded spring 23, thence to the upraised arm of the opposite free armature, whereupon the pivoted rocking motion of the free armature causes a reversal of direction, with the force finally being applied outwardly by the lower extension lug of the free armature, against its associated end of slot 27 in actuator arm 28. The limit of force which may be transmitted through the above described circuit is established by the pre-tension or compression adjustment of spring 23, usually adjusted so as to just reliably overcome the resistance of the tumbler.

It is seen that the above described path of forces is capable of functioning only when one armature is free or unenergized. In the case of a double pulse, an overlapping pulse, or simultaneous attraction of both armatures by their respective electromagnets, the effect will be an immediate downward movement of both armatures, with the resulting further compression of spring 23 and a resulting freeing of both ends of slot 27 of the normal spring pre-load force exerted by spring 23, by way of armatures 18 and 19 and the lower lugs 25 and 26 extending therefrom. In this case, the actuator arm 28 is freed of all spring and armature forces, and it will remain wherever last positioned by the energization of a single armature. This state of freedom, with the spring compressed, and the lower armature extension lugs disengaged from slot 27, might be described as the normal state where the relay is used in "inverted" circuits or current-normally-on circuits. In such cases, actuation is secured by the momentary interruption of the coil circuit opposite that last previously interrupted. In this case, actual operation of the actuator is effected by the momentary release of energy previously stored in spring 23 at the time of its compression.

The relay is capable of adjustment for great sensitivity when used in the "inverted," or current-normally-on class of circuitry. It is pointed out that the armatures operate from a closed state to an open state, to secure actuation. In such a case, if the spring pressure be adjusted as closely as possible to a state of equality with the holding power of the magnets, actuation can be secured with relatively feeble pulses applied to the coils in a bucking, or current decreasing direction. Under such closed gap conditions, pulses of low energy are capable of producing relatively great diminutions of flux and magnet holding power.

Thus the device operates an actuator in a sequential manner as a result of the application of two forces only in proper sequence. It will operate the actuator only when a single force of proper sequence is applied and any simultaneous dual application of forces or movements causes a mutual disabling of the two sides such that neither is effective until a single force of proper sequence is applied. During such double forcing, the actuator remains undisturbed, where last positioned.

The device also possesses the novel characteristic of functioning in an inverted sense, that is, with both forces applied continuously, the linkage is held non-operating or disabled, the actuator being undisturbed in the position last forced. The momentary removal of one only of the forces in proper sequence causes the actuator to be re-positioned or shifted by the remaining force. It will there remain if the broken force be restored, and likewise if both forces be removed. In other words, both forces either off or on, leave it where last positioned by a single force. The only condition which will change its position

is the single or initial application of that force not last applied singly.

The present device possesses an inherent memory or "fail safe" function whereby the accidental application of 5 simultaneous pulses to both coils, or the accidental overlap of the two pulses, disengages the armatures from the actuating arm for the duration of such double pulse. This results in a complete absence of indeterminate positioning. In the case of a double pulse, the actuating 10 arm and tumbler simply "sit" in the position last pulsed and refuse to move or change position until the coil circuits are cleared, the double pulse removed, and a clean pulse applied to the coil on the new or desired side. Thus the relay can be operated or thrown only by a clean pulse applied to the coil opposite that which was last energized.

The description thus far has been confined to a device utilizing a two position tumbler, in which only two positions of actuation may be secured. The spring loaded 15 interconnection of the two armatures makes possible the use of a tumbler of a triangular configuration. Such a 20 triangular device has its apex positioned generally upward, and notched for co-engagement with the corresponding notch at the lower end of the actuator arm 28. The base of this triangular piece is generally smaller 25 than the height dimension, and the outer margins of the base are fitted with suitable downward projecting knife edge or dome shaped portions which engage with depressions of corresponding form in the upper face of tumbler spring member 32. This triangular tumbler 30 possesses three positions of stability, since it may be tumbled right, left, or central, seating squarely on both sets of base projections.

It will be apparent that this triangular tumbler and 35 the actuator arm may be positioned right or left by pulsing the coils singly, in proper sequence. It may be centralized, or positioned in the central position by the simultaneous pulsing of both coils.

Countless circuit combinations may be devised to take 40 advantage of the flexibility inherent to this mechanism. Contact stacks may be incorporated to make or break in the right or left positions, and to make or break in the central position. Extreme flexibility is made possible by the incorporation of further contact stacks operated by 45 the armatures directly, in addition to those contacts operated by the actuator and tumbler. The use of shorting contacts in conjunction with "slow make" coils on the two electro-magnets, makes possible the use of the two position form of this relay in a "binary" or "flip-flop" 50 circuit where consecutive pulses applied repeatedly to the two coils in parallel, will cause a continuing flip-flop, or right-left-right-left response.

If desired, the L-shaped armature, dome shaped pivot and spring retention features may be embodied in relay executions other than those herein set forth.

55 The use of a triangular tumbler would permit the performance of three remote switching functions with only two coil or pulse circuits.

Having described my invention, I claim:

1. In a device of the character described, a pair of 60 movable members, actuator means adapted for a plurality of positional movements, means connecting said actuator means to said movable members, each of said movable members being actuated by said actuator means upon the actuation of the other of said movable members, said connecting means connecting said actuator means and said movable members allowing independent operation of said movable members upon simultaneous movement of both of said movable members in opposite directions and also connecting said members for simultaneous actuation of said movable members in the same direction, said connecting means including resilient means normally retaining said members in operative engagement with said actuating means and yieldable restraining means engaging said actuator means for nor-
- 65
- 70
- 75

normally holding said actuator means in one of said plurality of positions.

22. In a device of the character described, a pair of electromagnets, a pair of pivotally mounted armatures supported in operational position relative to said electromagnets, a pivotally mounted actuator member adapted for two positional movements by alternate energization of said electromagnets, yieldable restraining means engaging said actuator, normally holding said actuator member in either of two positions, a resilient connection normally connecting said armatures and means connecting said actuator member with said armatures for dependent simultaneous movement in one direction but allowing independent movement of said armatures in opposite directions whereby said armatures are disengaged from said actuator member.

23. In a device of the character described, a pair of electromagnets, a pair of pivotally mounted armatures supported in operational position relative to said electromagnets, a pivotally mounted actuator member adapted for two positional movements by alternate energization of said electromagnets, yieldable restraining means engaging said actuator member and normally holding said actuator member in either of two positions, a resilient connection normally connecting said armatures and means connecting said actuator member with said armatures for dependent simultaneous movement but allowing independent movement of said armatures whereby said armatures are disengaged from said actuator member.

24. In a device of the character described, a pair of pivotally mounted members, a pivotally mounted actuator member adapted for two positional movements, yieldable restraining means engaging said actuator and normally holding said actuator member in either of two positions, a resilient connection normally connecting said pivotally mounted members and means connecting said actuator member with said pivotally mounted members for dependent simultaneous movement but allowing independent movement of said movable members whereby said movable members are operatively disengaged from said actuator member and an overthrow member connected to said movable members and adapted to be actuated thereby.

25. In a device of the character described, a pair of electromagnets, a pair of pivotally mounted armatures supported in operational position relative to said electromagnets, a pivotally mounted actuator member adapted for two positional movements by alternate energization of said electromagnets, yieldable restraining means engaging said actuator normally holding said actuator member in either of two positions, a resilient connection normally connecting said armatures and means connecting said actuator member with said armatures for dependent simultaneous movement in one direction but allowing independent movement of said armatures in op-

posite directions whereby said armatures are disengaged from said actuator member and an overthrow member connected to said armatures and adapted to be actuated thereby.

26. In a device of the character described, a pair of electromagnets, a pair of pivotally mounted armatures supported in operational position relative to said electromagnets, a pivotally mounted actuator member adapted for two positional movements by alternate energization of said electromagnets, yieldable restraining means engaging said actuator normally holding said actuator member in either of two positions, a resilient connection normally connecting said armatures and means connecting said actuator member with said armatures for dependent simultaneous movement in one direction but allowing independent movement of said armatures in opposite directions whereby said armatures are disengaged from said actuator member and an overthrow member connected to said armatures and adapted to be actuated thereby.

27. In a device of the character described, a pair of electromagnets, a pair of pivotally mounted armatures supported in operational position relative to said electromagnets, a pivotally mounted actuator member adapted for two positional movements by alternate energization of said electromagnets, yieldable restraining means engaging said actuator member and normally holding said actuator member in either of two positions, a resilient connection normally connecting said armatures and means connecting said actuator member with said armatures for dependent simultaneous movement but allowing independent movement of said armatures whereby said armatures are disengaged from said actuator member and an overthrow member connected to said armatures and adapted to be actuated thereby.
